TREATING PETROLEUM DISTILLATES

John G. Browder, Houston, Tex., assignor, by
mesne assignments, to Standard Oil Develop-
ment Company, Elizabeth, N. J., a corporation
of Delaware

No Drawing. Application February 19, 1949,
Serial No. 77,447

4 Claims. (Cl. 196—29)

1

The present invention is directed to a method for treating sour petroleum distillates. More particularly, the invention is directed to the sweetening of sour petroleum distillates in the presence of an alkali metal hydroxide and a mild oxidizing agent.

Prior to the present invention, it has been known to treat sour petroleum distillates with aqueous alkaline solutions, such as solutions of alkali metal hydroxide, to remove hydrogen sulfide and other acidic bodies, following which the sour distillates were treated with sodium plumbite solution to convert deleterious sulfur compounds to compounds which are largely innocuous. This and other prior art processes relied on the addition of sulfur to cause the conversion of the sulfur compounds from mercaptans to disulfides. Other processes convert the undesirable compounds by means of lead sulfide, which is then separated from the gasoline. Frequently, the separation of lead sulfide from the gasoline was not complete, and, consequently, some was carried over into storage, which was disadvantageous. Furthermore, the addition of sulfur to gasoline frequently impaired the octane number level of the gasoline since it is well known that sulfur and its compounds affect gasoline detrimentally.

Efforts have been made in the prior art to remedy this situation, and the workers in the field have turned to adding certain compounds, such as phenols and amines, to alkaline solutions, such as sodium hydroxide, to cause conversion through an oxidation mechanism of the deleterious compounds in the sour naphtha. Frequently such expedients are unsatisfactory in not completely sweetening the product and an after-treatment, by one of the well known sweetening procedures, becomes necessary.

From the foregoing discussion of the prior art, it will be seen that the petroleum refining industry has been faced with a problem of converting deleterious sulfur compounds present in petroleum distillates to those which do not detrimentally affect the quality of the product.

It is, therefore, the main object of the present invention to provide a treating process in which improved results are obtained in converting objectionable sulfur compounds to harmless bodies.

Another object of the present invention is to provide an improved sweetening process in which an active material is added to the petroleum distillate being sweetened to catalyze the conversion of deleterious sulfur compounds.

Another object of the present invention is to

2

provide an improved sweetening process in which small amounts of catalytic reagents are employed.

In the foregoing discussion of the prior art, it will be seen that the prior art workers added compounds such as phenols and amines to the alkaline solutions which were employed to treat sour petroleum distillates. I have now found that, in distinction to the prior art workers, improved results may be obtained by adding catalytic amounts of a benzenoid compound selected from the group consisting of the amines and phenols to the sour petroleum distillate rather than to the alkaline solution. Therefore, in accordance with the present invention, the foregoing objects may be obtained by adding to sour petroleum distillates a catalytic amount of a benzenoid compound selected from the groups consisting of phenols and amines and then contacting the sour distillate containing the substituted benzenoid compound with a very small catalytic quantity of a solution of an alkali metal hydroxide while maintaining in contact therewith a mild oxidizing agent.

Accordingly, it may be seen that the present invention may be described briefly as involving treating a sour petroleum distillate boiling in the range from about 50° to 750° F. by contacting the distillate with a solution of an alkali metal hydroxide while maintaining in the sour distillate a catalytic amount of a benzenoid compound selected from the group consisting of the amines and phenols and adding to the contacted mixture a mild oxidizing agent sufficient to sweeten said distillate, following which the alkali metal hydroxide is separated from the contacted distillate.

The benzenoid compounds from the group consisting of amines and phenols, which find use in the present invention, may be illustrated by hydroquinone, cresols, catechol, pyrogallol, xylenols, crude petroleum phenols, tertiary amyl phenol, phenol, beta naphthol, amino phenols, such as p-amino phenol, the phenylenediamines such as ortho, meta, and paraphenylenediamine, N,N'-di-sec-butyl-p-phenylenediamine, and other amines and phenols.

These compounds may be employed in amounts, based on the naphtha, varying from 0.001 to 1.0 per cent by volume, with a preferred range from about 0.01 to 0.15 per cent by volume. It is to be emphasized that the specified amount of the benzenoid compound selected from the group consisting of the amines and phenols should be added to the naphtha and not to the alkaline solution.

The alkaline solution employed in the present invention should be a solution of an alkali metal hydroxide. Preferably the solution should be an aqueous solution having a Baumé gravity in the range from about 30° to 50° Bé. but solutions of lower strengths may be used under some conditions. For example, a 40° Bé. aqueous solution of sodium hydroxide gives satisfactory results.

The alkali metal hydroxide may be lithium, sodium, or potassium hydroxide, but sodium hydroxide will be preferred on account of its availability.

The temperature at which the treating operation is conducted will usually be atmospheric temperature and may range from about 60° F. up to about 200° F. and sometimes higher depending on the boiling range and type of the stock being treated. A preferred temperature range will be from about 70° to about 95° F. Satisfactory results have been obtained at atmospheric temperatures encountered in the Texas Gulf Coast area.

The present invention will be further illustrated by the following examples.

EXAMPLE I

A hydrogen sulfide free high sulfur petroleum distillate boiling in the kerosene boiling range, having a copper number of 41, was divided into three portions. One portion was treated by contacting with 5% by volume of 40° Bé. sodium hydroxide solution in the presence of 3 times the theoretical amount of oxygen required to sweeten the naphtha. The second portion was contacted with 5% by volume of 40° Bé. sodium hydroxide solution to which had been added 0.1% by volume of crude petroleum phenols based on the naphtha. This treatment was also conducted in the presence of 3 times the theoretical amount of oxygen necessary to sweeten the naphtha. The third portion had added to it 0.1% by weight of crude petroleum phenols based on the naphtha and then was contacted with 1% by volume of 40° Bé. caustic in the presence of 3 times the theoretical amount of oxygen required to sweeten. The copper numbers of the three treated samples were then tested immediately and after 1, 5, and 22 hours' settling time. The results of these tests are presented in Table I in which the first column shows the treatment with 40° Bé. caustic; the second column gives the results on the portion treated with sodium hydroxide containing petroleum phenols; and the third column gives results of the portion treated in accordance with the present invention.

Table I

Copper No. of Naphtha After Settling For, Hours	1	2	3
0.....	41	39	18
1.....	40	40	11
5.....	32	32	4
22.....	35	24	0

It will be seen from the data in the foregoing table that the portion treated only with caustic was not materially changed in its characteristics, the copper number dropping from 41 to 35 after 22 hours' standing. It will also be noted that the portion treated with caustic to which petroleum phenols had been added had its copper number reduced after the treatment from 41 to 39, which was reduced after 22 hours' standing to 24 which is a very sour stock and is unsuitable for commercial purposes. It will be noted, however, that the portion of the naphtha

treated in accordance with the present invention had its copper number reduced from 41 to 18 which after 1 hour had dropped to 11 and after 5 hours to 4 and after 22 hours to a 0 copper number and also was found to pass the well known "doctor" test. These results conclusively demonstrate that adding the petroleum phenols to the naphtha rather than to the sodium hydroxide allows vastly improved results with smaller amounts of reagent than was possible heretofore.

EXAMPLE II

In this run a portion of hydrogen sulfide free kerosene having a copper number of 52 was divided into four portions. One portion was contacted with 5% by volume of 40° Bé. sodium hydroxide solution and contacted with 300% of the theoretical amount of oxygen required to sweeten. The second portion was contacted with 5% by volume of 40° Bé. sodium hydroxide which was saturated with petroleum phenols, and also contacted with 300% of the theoretical amount of oxygen required to sweeten. The third portion had added to the kerosene approximately 0.003% by volume of N,N'-di-sec-butyl-p-phenylenediamine whereas the fourth portion had added to it 0.01% by volume of N,N'-di-sec-butyl-p-phenylenediamine. These two portions were then treated in contact with 300% of the theoretical amount of oxygen with 1 and 0.5% by volume, respectively, of a solution of 40° Bé. sodium hydroxide.

The four portions treated as described were then tested for copper number after the treatment and after standing for 1, 3, 5, and 20 hours. The results of these tests are shown in the following table in which the first column shows the treat with the sodium hydroxide solution and oxygen; the second column shows the treat with oxygen and sodium hydroxide to which had been added petroleum phenols; while the third and fourth columns illustrate the practice of the present invention with varying amounts of N,N'-di-sec-butyl-p-phenylenediamine, 40° Bé. sodium hydroxide solution, and oxygen.

Table II

Copper No. of Naphtha After Settling For, Hours	1	2	3	4
0.....	52	49	52	52
1.....	51	51	35	
3.....	50	47	48	29
5.....	49	41	42	23
20.....	44	30	30	14

It will be seen from the foregoing data that the treatment with 5% 40° Bé sodium hydroxide reduced the copper number of the stock from 52 to 44 after 20 hours' standing while, when the petroleum phenols were added to the caustic, the copper number was reduced after treatment from 52 to 49 and then dropped slowly after 20 hours' standing to 30, again which is a relatively sour stock. The data on the runs in accordance with the present invention show that in the run where 0.003% by volume of N,N'-di-sec-butyl-p-phenylenediamine was used, the amount is insufficient to give complete sweetening whereas 0.1% by volume reduced the copper number from 52 to 14 after 20 hours' standing, which is appreciably better than the results obtained in the prior art processes. These data further show that when employing 0.1% by volume of N,N'-di-sec-butyl-p-phenylenediamine in accordance with the

present invention, the stock will slowly sweeten on standing.

EXAMPLE III

In another run in accordance with the present invention, five portions of a hydrogen sulfide free low copper number catalytically cracked naphtha were obtained. One portion was contacted with 300% of the theoretical amount of oxygen to sweeten in the presence of 5% by volume of a 40° Bé. sodium hydroxide solution saturated with petroleum phenols. The second portion was also contacted with 300% of the theoretical amount of oxygen, but in this case 1% of 40° Bé. sodium hydroxide solution containing no petroleum phenols was employed. The third portion had added to it approximately 0.004% by volume of N,N'-di-sec-butyl-p-phenylenediamine and was contacted with 300% of the theoretical amount of oxygen necessary to sweeten, in the absence of sodium hydroxide. The fourth portion had added to it approximately 0.004% by volume of N,N'-di-sec-butyl-p-phenylenediamine and then was contacted in the presence of 300% of the theoretical amount of oxygen required to sweeten, with 1% by volume of 40° Bé. sodium hydroxide. The fifth portion was contacted similarly to the fourth portion with the difference that no oxygen was added other than that present in the treating vessel.

The naphtha, after the foregoing treatments, were tested for copper number immediately after the treat and after standing 1, 3, 5, 20, and 70 hours. The results of these tests are presented in the following table in which the first column gives the results of the tests on the naphtha treated with oxygen and with caustic to which had been added the petroleum phenols. The second column presents the results of the tests on the naphtha treated with 1% by volume of caustic and oxygen, while the third column gives the results on the naphtha to which had been added approximately 0.004% by volume of N,N'-di-sec-butyl-p-phenylenediamine and treated with 300% of the theoretical amount of oxygen required to sweeten in the absence of caustic. The fourth column presents data on the process of the present invention in which the N,N'-di-sec-butyl-p-phenylenediamine was added to the naphtha and 300% of the theoretical amount of oxygen employed in the presence of 40° Bé. caustic to sweeten. In the fifth column giving data on a process in accordance with the present invention, the only oxygen employed was that present in the treating reagent.

Table III

Copper Number After Reacting For	1	2	3	4	5
0 Hour.....	1.0	2.0	3.0	2	2
1 Hour.....	1.0	2.0	3.0	0	0
3 Hours.....	1.0	2.0	3.0	Passes	Passes
5 Hours.....	1.0	2.0	3.0	Doctor	Doctor
20 Hours.....	1.0	2.0	3.0	Test	Test
70 Hours.....	1.0	2.0	3.0		

It is seen from these results that the process in which N,N'-di-sec-butyl-p-phenylenediamine is added to the naphtha and the naphtha subsequently contacted with caustic and oxygen results in complete sweetening of the naphtha after one hour. A similar result is obtained when employing N,N'-di-sec-butyl-p-phenylenediamine in the naphtha in the presence of caustic and the oxygen present in the treating vessel. It will

be noted, however, that sweetening was not obtained when crude petroleum phenols were added to the caustic, nor when the N,N'-di-sec-butyl-p-phenylenediamine was added to the naphtha and the naphtha contacted with oxygen in the absence of sodium hydroxide. Similarly, when no N,N'-sec-butyl-p-phenylenediamine was added to the naphtha and the naphtha was contacted with the sodium hydroxide in the presence of 300% by volume of the theoretical amount of oxygen required for sweetening, sweetening was not obtained. It will be seen, therefore, that it is necessary to add the substituted benzenoid compound selected from the group consisting of the amines and phenols to the naphtha and then contact the naphtha containing the benzenoid compound with oxygen and caustic. Adding a substituted benzenoid compound to the sodium hydroxide solution is not effective and neither is the adding of N,N'-di-sec-butyl-1-phenylenediamine to the naphtha effective in the absence of the sodium hydroxide. It is believed significant that complete sweetening was obtained in accordance with the present invention after one hour whereas after 70 hours' complete sweetening was not obtained in the prior art processes.

EXAMPLE IV

In this example, a hydrogen sulfide free kerosene which was a solvent raffinate having a copper number of 50 and a Saybolt color of 20, was divided into two parts. To one part was added 0.05% by volume of hydroquinone and the mixture was then agitated for two minutes in an agitator equipped with paddles operating at 1200 revolutions per minute, in the presence of three times the theoretical amount of oxygen, with 5% by volume, based on the kerosene, of 40° Bé. sodium hydroxide. The second portion was contacted with 15% Bé. sodium hydroxide solution to which had been added 0.05% by volume, based on the kerosene, of hydroquinone and then was agitated violently for two minutes in an agitator equipped with paddles operating at 1200 revolutions per minute in the presence of three times the theoretical amount of oxygen required to sweeten. The two treated kerosenes were separated from the caustic solutions and then tested for copper number with the results appearing in Table IV in which the data in column 1 represent the treatment in accordance with the present invention in which the hydroquinone was added to the kerosene and the data in column 2 represents the prior art method in which the hydroquinone was added to the dilute sodium hydroxide.

Table IV

Copper No.....	1	2
Immediately.....		28 47
After 1 Hour.....		30 40
After 3 Hours.....		29 32
After 24 Hours.....		26 32

It will be apparent from the data in Table IV that the kerosene treated in accordance with the present invention had a much lower copper number than that treated in accordance with the prior art techniques in which the hydroquinone was added to the sodium hydroxide solution.

EXAMPLE V

In this example a hydrogen sulfide free kerosene, which was a solvent raffinate having a

copper number of 40, was divided into 6 parts. One part was contacted with 1% of 50° Bé. sodium hydroxide solution in an agitator equipped with paddles operating at 1200 revolutions per minute for two minutes, the sodium hydroxide solution separated, and the copper number determined immediately and after standing for 1, 3, 5, and 20 hours. The other five portions had added to them, respectively, beta naphthol, pyragallol, para-aminol phenol, tertiary amyl phenol, and phenol in an amount corresponding to 1 gram of the compound per liter of the kerosene. The five portions of kerosene containing the various compounds mentioned were then separately contacted with 1% by volume, based on the kerosene, of 50° Bé. sodium hydroxide solution for two minutes in an agitator equipped with paddles operating at 1200 revolutions per minute in the presence of three times the theoretical amount of oxygen required to sweeten. After the contact time specified, the sodium hydroxide solution was separated from the five portions of kerosene and they were then tested for copper number immediately and after standing for 1, 3, 5, and 20 hours. The results of these tests are shown in Table V.

Table V

Benzoid Compound	None	Beta Naphthol	Pyro-gallol	p-amino phenol	t-amyl phenol	phenol
Cu No. Before Treat.	40	40	40	40	40	40
Cu No. After Treat:						
Immediately After	35	21	27	35	32	25
1 Hour After	25	21	31	31	25	-----
3 Hours After	25	25	28	30	20	-----
5 Hours After	25	25	-----	-----	-----	-----
20 Hours After	20	10	8	15	10	3

From the results in the foregoing Table V, it will be immediately apparent that each of the benzenoid compounds employed in this example results in a marked lowering of the copper number of the treated naphtha, the effect of the phenol being particularly beneficial. In each case, it will be seen that the treating reagent in the kerosene gave appreciably better results than when the kerosene contained no additive at all.

EXAMPLE VI

In a sweetening operation in accordance with the present invention the stock treated was a naphtha comprising a mixture of virgin, catalytically cracked, thermally cracked, polymer and alkylate stocks, hydrogen sulfide, acidic bodies, and sufficient mercaptans to cause it to have a copper number of eleven. Preliminary to sweetening, this stock was subjected to a first caustic wash (aqueous sodium hydroxide) for hydrogen sulfide removal, being continuously charged at the rate of 500 bbls./hour, to an incorporator just prior to which 5° Bé. caustic, at the rate of 25 bbls./hour was injected into the naphtha stream. The mixture was then allowed to settle in a system of two settlers in series, having a total residence time of 1½ hours. The caustic solution drawn off from the bottom of the settlers was recycled to the injection point ahead of the first incorporator. The naphtha effluent from the first wash, now free of hydrogen sulfide, was then subjected to a second caustic wash for removal of undesirable acidic compounds, which degrade the quality of the sweetened produce if allowed to remain in the stock and which also have been found to attack the amine which is added to promote sweetening as

described herebelow. This second caustic wash was carried out similar to the first caustic wash described above; however, the 12° Bé. caustic solution employed, which, after settling was recycled at the rate of 25 bbls./hour. The naphtha effluent from the second wash, now free of undesirable acidic compounds, was then charged to the actual sweetening step. At a first injection point in the pipe leading from the settlers to a third incorporator, 10.5 gallons/hour of crude petroleum phenols and 6.5 pounds/hour of N,N'-di-sec-butyl-p-phenylenediamine were added to the naphtha stream. At a second injection point 120 standard cubic feet per hour of oxygen (200% of the amount theoretically required to convert mercaptans present in the original charge to disulfide) was injected into the naphtha stream, and, at a third injection point 45° Bé. caustic, recycled from the settlers as described below, was injected at the rate of 25 bbls./hour. The mixture then passed through the third incorporator to two settlers in series, and, after a total residence time of 1½ hours, the separated naphtha passed on to tankage, and the separated caustic was recycled to the injection point ahead of the third incorporator without being subjected to any

intermediate treatment. The naphtha passing to tankage was found to have a copper number of 3.0 and after 40 hours of residence time in tankage the naphtha was found to have a zero copper number and pass the doctor test.

This particular run was continued for 36 hours, during which time the 45° Bé. caustic employed in the sweetening step was continuously recycled from the settlers to the injection point ahead of the incorporator at the rate of about 25 bbls./hour without losing its effectiveness as a sweetening catalyst. No make-up caustic was required or employed. This run effectively illustrates the catalytic action of the alkali metal hydroxide solution since it may be re-used without requiring regeneration.

In the foregoing examples, the improvement obtained in the present invention has been illustrated by the copper number test. This is a well known analytical procedure employed in the petroleum industry. A description of the method of test may be found in "U. O. P. Laboratory Test Methods for Petroleum and its Products," third edition, page H-61, Universal Oil Products Company, Chicago, 1947. This test is a measure of the mercaptan sulfur content of the oil being tested.

In the practice of the present invention, it is to be understood that the sour petroleum distillates employed as feed stocks are free from or deficient in the catalytic benzenoid compound and will not sweeten in contact with a mild oxidizing agent and alkali metal hydroxide as disclosed and claimed herein. My invention is concerned with adding to and/or maintaining in such stocks the stated amount of the compounds of the types mentioned.

The invention has been illustrated by reference to the employment of "petroleum phenols." This terminology has been accepted in the patent literature. The petroleum phenols may be obtained by contacting cracked heating oil fractions boiling between 400° to 700° F., and preferably those fractions from thermal cracking operation, with a strong alkali solution, such as a 40° Bé. sodium hydroxide solution. This extraction causes the separation of a mixture of phenolic and naphthenic salts which may be completely acidified to release the "crude" petroleum phenols employed in the practice of the present invention and to illustrate the beneficial results inuring thereto. The crude petroleum phenol containing fraction may be refined to obtain purified phenolic material by modification of the above process in which the selected fraction is extracted with a 40° Bé. sodium hydroxide solution and the solution then partially acidified to release only the phenolic compounds, leaving the naphthenic salts in the alkaline layer. The separated phenolic compounds may be distilled to recover the desired fraction.

Although not illustrated by the several examples, one of the particular advantages of the present invention resides in the catalytic effect of the alkali metal hydroxide solution. The alkali metal hydroxide appears to function as a true catalyst since the small amount used may be recycled to treat large quantities of the sour petroleum distillate. A small amount of the alkali metal hydroxide solution may be entrained in the treated naphtha, and, therefore, it may be necessary to replace the entrained amount with fresh solution. In short, it is contemplated in the practice of the present invention that the alkali metal hydroxide solution will be reused over and over again since it is not necessary to regenerate the alkali metal hydroxide solution.

The invention has been described and illustrated by employment of a mild oxidizing agent such as oxygen. It is contemplated that mixtures of oxygen with other gases, such as air, may be employed. It is also contemplated that other mild oxidizing agents such as peroxides, permanganates, and the like may be used. For example, a hydrogen peroxide solution may be employed as the mild oxidizing agent.

In practicing the present invention, it is to be understood that the petroleum distillate may be subjected to a preliminary treatment for removal of hydrogen sulfide if the distillate contains hydrogen sulfide. Such preliminary treatment may include washing with a dilute alkali metal hydroxide solution or blowing with a free-oxygen containing gas such as air. If hydrogen sulfide or other acidic compounds are present and not removed, the alkali metal hydroxide solution employed as the catalyst may very quickly become seriously depleted in activity.

In the practice of the invention, it will be desirable to use an amount of oxygen in excess of the theoretical required to sweeten the sour petroleum distillate. Ordinarily, an amount of about 300% of the theoretical amount to sweeten may be employed. However, sweetening in accordance with the present invention may be obtained with considerably lesser quantities of oxygen. In fact, sweetening may be obtained in some cases by contact with the oxygen present in the treating vessel. It will be desirable to employ an amount of oxidizing agent at least equivalent to the theoretical amount required to sweeten.

The invention has been described and exem- 75

plified by employment of 0.5 to 1.0% by volume of the catalytic alkali metal hydroxide solution. It is contemplated that as little as 0.1 and as much as 5% by volume, or more, of the alkali metal hydroxide solution, based on the sour naphtha, may be employed. Very good results, however, are obtained with 1% by volume and this amount may be preferred.

The nature and objects of the present invention having been completely described and illustrated, what I wish to claim as new and useful and to secure by Letters Patent is:

1. A method for sweetening a sour petroleum distillate containing mercaptans and having a final boiling point no greater than 750° F. which comprises adding to said distillate a small but effective catalytic amount of a benzenoid compound selected from the group consisting of the amines and phenols and then contacting the sour distillate containing the benzenoid compound with a catalytic amount no more than 5% by volume of a solution of an alkali metal hydroxide while adding a sufficient amount of a mild oxidizing agent to convert the mercaptans to disulfides and to obtain a sweetened distillate.
2. A method for sweetening a sour petroleum distillate containing mercaptans and having a final boiling point no greater than 750° F. which comprises adding to said distillate an amount of a benzenoid compound selected from the group consisting of the amines and phenols in the range from 0.001 to 1.0 per cent by volume of said distillate, then contacting the sour distillate containing the benzenoid compound with a sodium hydroxide solution in an amount in the range between 0.1 and 5% by volume while adding a sufficient amount of air to convert the mercaptans to disulfides, and separating the contacted distillate from said sodium hydroxide solution to obtain a sweetened distillate.
3. A method for sweetening a sour petroleum distillate containing mercaptans and having a final boiling point no greater than 750° F. which comprises adding to said distillate a small but effective catalytic amount of a benzenoid compound selected from the group consisting of the amines and phenols, then contacting the sour distillate containing the benzenoid compound with a catalytic amount no more than 5% by volume of a solution of an alkali metal hydroxide while adding a sufficient amount of a mild oxidizing agent to convert the mercaptans to disulfides, separating the contacted distillate from said alkali metal hydroxide solution to obtain a sweetened distillate and contacting additional quantities of said sour distillate containing the benzenoid compound with said separated alkali metal hydroxide solution.
4. A method for sweetening a sour petroleum distillate containing mercaptans and having a final boiling point no greater than 750° F. which comprises adding to said distillate an amount of a benzenoid compound selected from the group consisting of the amines and phenols in the range from 0.001 to 1.0 per cent by volume of said distillate, then contacting the sour distillate containing the benzenoid compound with an amount in the range between 0.1 and 5% by volume of a sodium hydroxide solution while adding a sufficient amount of air to convert the mercaptans to disulfides, separating the contacted distillate from said sodium hydroxide solution to obtain a sweetened distillate, and contacting additional quantities of said sour distillate containing the ben-

zenoid compound with said separated sodium hydroxide solution.
